CONCRETE ROAD FORM

Filed May 9, 1923

Patented Sept. 9, 1924.

1,507,750

UNITED STATES PATENT OFFICE.

CONRAD MAGNUS MOLSTAD, OF FOSSTON, MINNESOTA.

CONCRETE-ROAD FORM.

Application filed May 9, 1923. Serial No. 637,853.

To all whom it may concern:

Be it known that I, CONRAD MAGNUS MOLSTAD, a citizen of the United States, and a resident of Fosston, in the county of Polk 5 and State of Minnesota, have invented a new and useful Improvement in Concrete-Road Forms, of which the following is a full, clear, and exact description.

My invention relates to improvements in 10 concrete road forms, and more particularly to that type of form which is intended for repeated use, and which may be moved from one job to another, and it consists in the combinations, constructions, and arrangements herein described and claimed.

An object of my invention is to provide 20 a road form of the character described that is exceedingly strong and rigid by virtue of its tubular construction which renders lateral warpage by excessive strain practically impossible.

A further object of my invention is to provide a road form of the character described in which the ends of the tubular sections 25 are reenforced to prevent distortion where the strain upon the forms is the greatest.

A further object of my invention is to provide a road form of the character described 30 in which the hollow sections are closed at their outer ends, thereby precluding the possibility of the accumulation of concrete and the like within the form.

A further object of my invention is to 35 provide a road form of the character described in which individual sections may be removed after the form has been set, by merely loosening the adjacent stakes.

A further object of my invention is to 40 provide a road form of the character described in which novel means for supporting the ends of the form is employed, which permits the lateral adjustment of the forms relative to one another without sacrificing 45 the rigidity of support which is an absolute essential characteristic to the successful functioning of the forms. This novel supporting structure also permits the pitch of one form relative to the other to be varied 50 as in paving an up or down grade stretch.

A further object of my invention is to provide a road form of the character described that is extremely simple in construction, that may be quickly and easily set or

taken up, and which is thoroughly practical 55 for the purpose intended.

Other objects and advantages will appear in the following specification, and the novel features of the invention will be particularly pointed out in the appended claims. 60

My invention is illustrated in the accompanying drawings, forming part of this application, in which—

Figure 1 is a side elevation of an embodiment of my invention with a portion thereof 65 broken away.

Figure 2 is an enlarged sectional view along the line 2—2 of Figure 1,

Figure 3 is a top plan view of the form 70 supporting horse,

Figure 4 is a fragmentary bottom view of one of the sections, and

Figure 5 is a top view of a portion of the mechanism illustrated in Figure 1.

In carrying out my invention, I make use 75 of a plurality of substantially tubular sections, three of which I have indicated at 1, 2, and 3, in Figure 1 of the drawing. These tubular sections have the appearance in cross section of a trapezoid, and are formed from a single sheet of steel having its adjacent edges 4 and 5 overlapped and electrically welded to one another. The overlapping portions 4 and 5 are on the base or the larger of the two parallel sides (see Figure 2). 80 Each of the tubular sections has an angular recess 6 cut in the bottom wall 7 thereof at each end (see Figure 4).

A saddle comprising a sheet of steel bent 90 laterally to form the interior side walls and top wall of the tubular forms is inserted within the forms at their outer ends. The saddle is constructed of a steel strip that is thicker at its outermost end than at its innermost end (see Figure 1 and the dotted 95 representations in Figures 4 and 5). The three sides of the saddle are indicated at 9, 10, and 11 in Figure 2, and the outer edge of the saddle is flush with the outer edge of the form. The saddle so formed is electrically welded to the inner sides of the tubular sections so that the saddles virtually form an integral part of the sections. In order that the tubular sections may be entirely closed to preclude the entrance of extraneous substances, such as cement and the like, a metal sheet 8 cut to conform with the interior section of the form is secured to the 100 105

inner edges of the saddle as shown in Figure 1. This closure is not essential, but aids greatly in prolonging the life of the forms and lends somewhat to the strength of the 5 saddle.

One of the most important advantages of the provision of this saddle, besides its intended functions, is that the relatively thick outer end of the saddle greatly reinforces 10 the outer ends of the forms. This is of utmost importance, since the strain upon the form at this point is at its maximum and it is apparent that any distortion of the ends of the form would bar the successful operation 15 of the complete form.

Means for supporting the sections 1, 2, and 3, and others with their ends abutting one another as in forming a continuous road form, is provided in a device which I choose 20 to call a horse. This horse is constructed of a flat steel plate 12 somewhat longer than it is wide and having a circular opening 13 therethrough adjacent the outer side 14 thereof and midway between the ends 15 of 25 the plate. A second steel plate 16 having an opening therein in exact registration with the opening 13 is electrically welded to the plate 12 (see Figures 2 and 3). This plate 16 has an integral upwardly extending member 17 fashioned in the shape of a truncated pyramid and disposed with its vertical surface 18 parallel with the inner side surface 19 of the plate 12.

Means for fixing the horses against movement 35 relative to the ground as in preparing the horses for the support of the sections, is provided in a plurality of stakes, one for each of the openings 13 through the superimposed plates 12 and 16. These stakes 40 have a round body member 20 and are sharp at their lower ends to pierce the clay or soil into which they are to be driven, and a head portion 21 having a substantially flat top and two flat side walls. The remaining two 45 side walls are rounded, as shown at 22, to facilitate the engagement of the head with the adjacent wall of the sections when in place.

From the foregoing description of the various parts of the device, the operation 50 thereof may be readily understood. It should be noted at this time from an inspection of Figure 1 that my improved road form necessitates the use of only one stake for each section, there being one horse for 55 each section employed, each of which supports the adjacent and abutting ends of two sections, and that therefore I have reduced the number of supporting members and associate fastening stakes to a minimum, together with the reduction in the cost of laying 60 and setting of the form.

In laying my improved road form, it is necessary first to place the horses at the proper distances from one another at the edge 65

of the road in the positions indicated by the survey. The stakes are then driven through the openings 13 of the plates 12 and 16 and into the earth. The stakes are driven only partially into the earth at this time. The 70 next step in applying my improved road form is to place the sections on the horses so that their abutting ends overlie the exact center of the upwardly extending portion 17 of the horse. The outer peripheral edge of 75 the portion 9 of the saddle will therefore bear directly upon the top wall 23 of the portion 17, and the peripheral edges of the portions 10 and 11 will contact with the vertical wall 18 and the front sloping wall 24 80 of the portion 17.

It is then merely necessary to drive the stakes so that the adjacent curved walls 22 of the head 21 are moved into close engagement with the adjacent sides of the tubular sections. 85

Let us assume that the form to be used is for a curved portion of the road and that therefore the sections must be disposed at an angle from one another to conform with the required bend in the finished road. My improved road form is particularly well fitted for such use in that the rigidity of support is not sacrificed to the smallest extent by a movement of the forms relative to one another. This may be more clearly understood from an inspection of the dotted line 90 position of the saddle 8 as viewed in Figures 4 and 5.

Let us assume also that one of the sections 100 must be removed after the form has been completed for some reason, such as the movement of a truck or other vehicle from the road bed to the side. In the ordinary road form construction, it is necessary to break the connections between the form by either lifting two of the adjacent forms, which ordinarily interlock with one another to obtain the rigidity which I obtain with the use of my improved form, or proceed 105 with a difficult and lengthy operation in disassembling the supporting mechanism. In my present road form, it is merely necessary to loosen the stakes adjacent to the section 110 to be removed, and to vertically lift the sections out of engagement with the horses. 115

I claim:

1. A device of the character described comprising a hollow tubular form, saddle members disposed within said form at each end thereof and having their supporting surfaces at a higher plane at their inner ends than at the outer ends of said saddle, and horses for supporting said saddles. 120

2. A device of the character described comprising a hollow tubular form, saddle members disposed within said form at each end thereof and having their supporting surfaces at a higher plane at their inner 125 ends than at the outer ends of said saddle, 130

horses for supporting said saddles, and stakes for securing said horses against movement on a supporting surface and for preventing the removal of said form from 5 said horses.

3. A device of the character described comprising a plurality of tubular forms arranged with abutting ends, saddles disposed within said forms at each end and arranged 10 to close the ends of said forms, and metal horses arranged to be fixed to the supporting surfaces and to support said saddles,

whereby said forms may be fixed against movement relative to the supporting surface. 15

4. In a device of the character described, a saddle arranged to be fixed at the end of a road form, said saddle having inclined support engaging surfaces, and a metal horse arranged to contact the lowermost of 20 said inclined supporting surfaces on said saddle, whereby said saddle may pivot vertically or laterally relative to said horse.

CONRAD MAGNUS MOLSTAD.
